UNITED STATES PATENT OFFICE

HARDIN L. HURN, OF LOUISVILLE, KENTUCKY

ERASER CLEANER

Application filed May 18, 1932. Serial No. 612,090.

This invention relates to new and useful improvements in apparatus for cleaning blackboard erasers, and comprises essentially a cabinet in which the erasers to be cleaned are mounted to revolve into contact with a rotary brush.

The object of the invention is to produce a portable device which can be very cheaply manufactured and used in school rooms for thoroughly cleansing blackboard erasers.

Another object of the invention is to provide a device of this character in which the erasers can be cleaned in an air tight container, thereby eliminating the raising of fine particles of chalk and the distribution thereof through air which must be breathed in the school rooms.

Other objects of the invention will become apparent as the detailed description thereof proceeds.

In the drawing:

Figure 1 is a horizontal section through the eraser cleaner illustrated in Figure 2; and

Figure 2 is a central vertical section through the said cleaner.

As shown in the drawing, the invention comprises a substantially rectangular cabinet having a base 1, side walls 2 and 3, end walls 4 and 5, and a top 6. The end wall 4 is provided with a rectangular aperture 7 adapted to permit a drawer 8 to be slid into and out of the cabinet along the base 1 and between the side walls 2 and 3. The drawer 8 is provided with a knob 9 to facilitate its movements into and out of the cabinet.

A drum designated generally by the reference numeral 10 is mounted to rotate in the cabinet. This drum comprises end walls 11 and 12 preferably polygonal in outline. As shown in the drawing, these ends are shaped to the outline of an octagon. However, the invention is not limited to any particular number of sides for the drum. With large cabinets, drums having a greater number of sides would be used. A drum having ten sides or panels would be found very convenient in portable cabinets, although they may extend to twelve, twenty, or thirty sides according to the dimensions of the cabinet.

For portable cabinets, the octagon or decagon shaped drums will be very practical.

The end walls 11 and 12 of the drum 10 form supports for panels 13, which, with the end walls, constitute an octagonal prism, each surface of which forms a base adapted to receive and support a blackboard eraser 14. In order to detachably support and position, the erasers 14, upon the panels 13, each panel is provided with a pair of spring clips 15. Each of these clips comprise a base plate 16 suitably apertured to receive means 17 for securing the clips to the panels 13. The base plate 16 connects with a flange 18 arranged substantially at an angle of 90 degrees to the said base; and this flange 18 is bent in the opposite direction to base 16 to form a yielding member 19 adapted to extend over the inclined side portions of the blackboard erasers 14.

As previously stated, these clips 15 are arranged in pairs, and the erasers 14 are adapted to be slid along the face of the panels 13 between the pairs of clips 15 until the end of the body or base of the eraser 14 is stopped by inturned lugs 20 at the end of the aforesaid clips. The other end of each clip is rounded off so as to avoid cutting contact with the hands of the person operating the device; and to facilitate entry of the eraser into the space on each panel between the pairs of spring clips.

The drum constructed as described, is secured to a shaft 21 passing rotatably through an aperture 22 formed in the side 3 of the cabinet. The shaft 21 extends also through apertures centrally bored in the end walls 11 and 12 of the drum; and one end of the shaft is screw-threaded to receive the nuts 23 and 24 for clamping the end wall 11 of the said drum to the said shaft 21.

The cabinet is provided on its inside with a pair of metallic bearing brackets 25 and 26 apertured to form journal bearings for the shaft 21. The bracket 25 is a strip of metal having its opposite ends bent over parallel to the main body of the bracket. The bent over part 27 of the bracket 25 is apertured to receive the shaft 21 and to form an additional support therefor. The other end

of the shaft 21 is supported rotatably in an aperture 28 formed in the return bent end 29 of the bracket 26. These brackets 25 and 26 are suitably secured, as by bolts 30, to the sides 2 and 3 of the cabinet. It will be noted from the drawing of Figure 1, that the ends 27 and 29 act as stops to limit the actual movement of the shaft 21 as well as to form journal bearings in which the aforesaid shaft 10 is rotatably mounted.

The other end of the bracket 25 is bent over to form a portion 31 apertured to receive the shaft 32 of a brush 33 which is rotatably mounted in the cabinet to contact with the 15 felt of the various blackboard erasers mounted on the rotatable drum 10. The other end of the shaft 32 is supported in a journal bearing bracket 33 formed in a part 34 bent over from the bracket 26 to form a bearing for one 20 end of the said shaft 32. The brush is preferably of the twisted wire core type and this core forms the shaft 32 journaled in the return bent parts 31 and 34 of the brackets 25 and 26, respectively.

25 The drum 10 is mounted to rotate at such height in the cabinet that the panels of the drum supporting the blackboard erasers project successively through an aperture 35 formed in the cover 36 of the cabinet. The 30 aperture 35 is closed by a curved cover 36 which is suitably hinged at one edge to the top 6. The cover 36 is provided with a flange 37 around its edges and this flange is adapted to seat on a gasket 38 of felt or similar material adapted to form, with said cover, an air tight closure for said cabinet. A thumb nut 39 rotatably mounted on the top 6 is positioned so that it can be turned across the flange 37 at the striking edge of the cover 36 40 to lock the cover securely in position when desired.

The cover 36 is preferably formed on an arc struck from the axis of shaft 21 as center. While the drum may be rotated in either direction, it is preferably rotated clockwise as 45 viewed in Figure 2 of the drawing. This rotation sets up a draft which directs the loose particles of chalk in the cover 36 downwardly on to the brush 33.

50 The brush 33 is wide enough to cover the entire surface of each eraser, and is rotated by the rotation of the drum 10. The brush is so positioned relative to the drum that its bristles mesh with the eraser felts, thereby 55 removing the greater part of the chalk dust which ordinarily accumulates between these felts. This arrangement enables the device to clean worn down felts, which would otherwise not come into direct cleaning contact 60 with the brush.

A baffle plate 40 is secured between the sides 2 and 3, and is arranged so as to trap the chalk dust, loosened from the erasers by the brush 33, and to direct this dust downwardly into the drawer 8. A second baffle

plate 41 is secured between the sides 2 and 3 and is designed to trap any chalk dust that may have passed the end of the plate 40. The inner edge of plate 41 extends close to the faces of the erasers 14 as they rotate toward the opening 35; and the plate 41 is positioned horizontally so as to deflect the dust downwardly into the drawer 8.

A skirt 42 is secured in the opening 35, and is shaped to continue the general outline of the cover 36 when the latter is closed. This skirt forms, with the cover 36, a means for creating a draft, as the drum rotates to direct the floating particles of dust directly against the brush 33 where it meshes with the felts of the erasers, and thereby practically eliminates all dust from the air within the cover at the completion of a cleaning operation.

While the eraser supporting part of the invention is shown in the form of a polygonal prism, the invention must not be considered as limited to the use of a prism for this purpose. It is obvious that as the sides of the prism increase in number, they will merge into a cylinder. It is, therefore, contemplated that this invention may, in its larger forms, employ a cylindrical drum instead of the polygonal one shown in the drawing. The essential feature of the drum is that it shall be so mounted in the cabinet that its periphery will be located sufficiently close to the opening in the top of the cabinet as to give ready access to the eraser holding clips for the purpose of removing or positioning the erasers in the aforesaid clips.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claim.

What I claim is:

A cabinet having an opening through the top thereof, a prism-shaped drum rotatably mounted in said cabinet and projecting through said opening, means for rotating said drum, a pair of eraser holding clips mounted on each face of the drum, a brush mounted in said cabinet adjacent said drum whereby its bristles mesh with the felts of the erasers as the drum is rotated, and an arcuate cover hinged to said top to close the opening over said drum, said cover being formed on an arc having its axis coincident with the axis of the drum, and being positioned adjacent the drum whereby the movement of the 120 erasers creates a draft in the direction of rotation of said drum.

In testimony whereof I affix my signature.

HARDIN L. HURN.
